United States Patent Office

Des. 205,029
Patented June 14, 1966

205,029

DOOR HANDLE

La Verne E. Clayton, Rockford, Ill., assignor to Amerock
Corporation, Rockford, Ill., a corporation of Illinois

Filed Nov. 18, 1965, Ser. No. 88,147

Term of patent 14 years

(Cl. D10—8)

FIGURE 1 is a side elevation of a door handle incorporating my new design, this being as viewed from the left of FIG. 2.

FIG. 2 is a front elevation of the door handle.

FIG. 3 is a top view of the door handle.

FIG. 4 is a side elevation as viewed from the right of FIG. 2.

FIG. 5 is a fragmentary sectional view taken along the line 5-5 in FIG. 2.

FIG. 6 is an enlarged sectional view taken along the line 6-6 in FIG. 2.

FIG. 7 is an enlarged sectional view taken along the line 7-7 in FIG. 2.

FIG. 8 is an enlarged sectional view taken along the line 8-8 in FIG. 2.

FIG. 9 is an enlarged sectional view taken along the line 9-9 in FIG. 2.

I claim:

The ornamental design for a door handle, substantially as shown.
